UNITED STATES PATENT OFFICE

WALTER WILLIAM CADWELL, OF LAGRANGE, GEORGIA

VENDING MACHINE

Application filed August 1, 1927. Serial No. 209,954.

5 My invention relates to vending machines and has particular reference to machines operated by coins. It is an object of the invention to provide a machine of this type which shall be compact in structure, simple in operation, and inexpensive to operate and which shall provide an attractive display of the wares vended in such a manner as to enable the would-be purchaser to select any one of several articles.

10 Referring to the accompanying drawings which are made a part hereof and on which similar reference characters indicate similar parts,

15 Figure 1 is a front elevation of the machine,

Figure 2, a vertical section taken on the line 2—2 of Fig. 1,

20 Figure 3, a horizontal section taken on the line 3—3 of Fig. 2,

Figure 4, a vertical section taken on the line 4—4 of Fig. 2, and

Figure 5, a section on line 5—5 of Fig. 4 showing the coin actuated mechanism.

25 In the drawings numeral 10 indicates the base of the machine which base may be cast from suitable material or stamped from sheet metal or other material. The lower portion of the base 10 has a plate 11 removably attached to the sides in any suitable manner. The base is provided with a cover plate 12. A transverse rib 12' beneath the plate 12 serves to strengthen the plate and avoids the necessity of having said plate 12

30 made of heavy material. One side of the base 10 has an opening 10'. An inclined plate 13 attached to the cover 12 at 14 extends through the opening 10' and is turned up at 13' to provide a ledge or trough for

35 receiving the vended article. The base 10 at its upper corners is provided with in-turned lugs 15 preferably cast integral with the base. Upon these lugs 15 are mounted posts 16. Screws 17 secure the plate 12

40 between the lugs 15 and the ends of the

posts 16. A cover plate 18 is secured upon the post 16 by means of screws 19. The posts 16, as shown in Fig. 3, are provided with longitudinal slots for holding the plates or casing elements 20. These plates are 50 preferably glass or other transparent material but not necessarily so. The rear plate is preferably hinged at 22 to provide a door 21 having a lock 23 to provide access to the interior of the machine for loading the same with articles to be sold. Mounted within the walls 20 is a revolving cabinet 25 provided with magazine chambers 26 for receiving articles to be dispensed, here shown as cigarettes 27.

55 The cabinet 25 is mounted so as to be selectively rotated with the shaft or pivot 28 mounted in a bearing 29 in the cover plate 18 and in the plate 12. A screw 14 in the plate 12 allows shaft 28 to be turned in the plate 12 as a bearing. The base 30 of the cabinet is provided with holes 31 into which a ball catch 32 is adapted to engage. This ball is held in a sleeve 33 positioned beneath the plate 12 and is kept in 60 position by a spring 34 held under tension by a cotter-pin 35. The cabinet may be rotated but will be stopped when the ball 32 registers with any one of the holes 31. The plurality of the magazine chambers 26 provide for a selective assortment of articles to 65 be sold.

70 . A square frame 36 is fixed to the shaft 38 above the machine to be rotatably moved therewith. This frame may carry any sign or preferably may carry an advertisement of each of the wares used in the machine, here shown as Riedmont or Westerfields.

75 Within the base of the machine are depending brackets 37 and 38 the same being 80 attached to the under side of the plate 12. The bracket 37 is U-shaped to provide two bearing surfaces 39 and 40, while the bracket 38 provides a bearing 41 for the shaft 42 upon which is mounted a slotted drum 43. 85 90

The slot 44 in the drum is adapted when properly positioned to receive the vended article. The shaft 42 fits within a slightly larger shaft 45 journaled in the bearing 46 in the base 10. A knob 47 is provided on the outer end of the shaft 45. On the inner end of the shaft 45 is a disk 48 having a lug 49 thereon. The adjacent end of the cylinder 43 has a pocket 50 therein. A spring 42' surrounds the opposite ends of the shaft 42 and is fastened at one end to the shaft 42 and at the other end to the bracket 37. This spring is positioned and tensioned so as to rotate the drum 43 to the position shown in Fig. 2. A plate 51 having two straight edges 52 and 53 is fixed to the cylinder 43 to rotate therewith. The straight edges 52 and 53 striking the lower surface of the plate 12 prevent rotation of the cylinder 43 beyond a predetermined degree. A housing 54 surrounds the disk 48 and the end of the cylinder 43 adjacent thereto. This housing has a slot 55 to provide an outlet for the coin into the interior of the base 10.

In the inclined edge of the cover 18 is a slot 56. This slot extends as an elongated passage down the side of the chamber 26 and into the pocket 50 in the ends of the cylinder 43 when this cylinder is in proper position.

The operation of the device will now be described:

The cabinet 25 is rotated to the position where the article sought to be purchased is at the front of the machine whereupon the ball catch 32 will hold the cabinet in position. A coin is then inserted in the slot 56 and passes down the slot to lodge in the pocket 50 in the end of the cylinder 43. The knob 47 is then rotated whereupon the lug 49 on the disk 48 engages the edge of the coin and locks the disk 48 to the cylinder 43. Rotation of the knob 47 will therefore rotate the cylinder 43 until the groove 44 registers beneath the magazine 26. A cigarette 27 will immediately drop into the slot 44. At the same time the coin will have been carried along against the inner side of the housing 54 until it registers with the opening 55 in this housing. The coin will then drop through the slot 55 into the chamber within the base of the machine. As soon as the coin drops from the pocket 50, the lug 49 is no longer keyed to the cylinder 43. The spring 42' will therefore reverse rotation of the cylinder 43 and bring the slot 44 to the position shown in Fig. 2 whereupon the cigarette will roll down the incline 13 to the pocket 13'.

For filling the machine with articles to be sold the magazines are rotated to register with the rear of the machine adjacent the door 21 whereupon the machine may be filled.

While I have shown my device as preferably used in the sale of cigarettes which in this case might be sold at a profit for a cent apiece, I do not mean to limit the use of my machine as a vending machine for cigarettes. Obviously, it might be used with equally good results as a machine for dispensing short lead pencils, crayons, or even candy, or any article that could be profitably sold for a coin of a given value.

It will be obvious to those skilled in the art that various changes may be made in my device without departing from the spirit of the invention, and I, therefore, do not limit myself to what is shown in the drawings and described in the specification, but only as set forth in the appended claims.

Having thus fully set forth my said invention, what I claim as new and desire to secure by Letters Patent, is:

1. A vending machine comprising a base, a case having transparent walls mounted upon the base, and supporting means for displaying an advertisement for goods to be sold by the machine, a cabinet rotatably mounted on the base and enclosed within the said case, means for rotating the cabinet and locking it in any one of several predetermined positions, a cylinder mounted in the base, said cylinder having a longitudinal groove for receiving the article to be vend-
ed, manually operable means for rotating said cylinder to cause the slot to register with the said chamber to receive an article to be vended, a pocket in the end of said cylinder adapted to receive a coin, a disk on said manually operable member having a lug thereon for engaging the coin to lock the manually operable member to the cylinder upon rotation of the former to rotate the cylinder, said lug serving to eject the coin and unlock the connection between the cylinder and the manually operable member at a predetermined period in the rotation, and means for reversely rotating the cylinder to return it to its normal position, substantially as set forth.

2. A vending machine comprising a base, a case mounted upon the base, a cabinet within the casing mounted upon the base and having compartments for holding goods to be sold, a slotted cylinder rotatably mounted in the base, a manually operable shaft mounted in the base in alignment with the said cylindrical member, a disk on the said shaft, said disk having a lug extending therefrom, a pocket in the end of the said cylindrical member adapted to engage an edge of the coin to lock the said shaft and the said cylindrical member together so that the latter may be rotated by the former, a housing encasing said disk and the pocket in said cylindrical member and so placed that rotation of the manually operable shaft will cause the lug to engage the coin and force

it against the inner wall of the said casing as it rotates the cylindrical member, the said lug operating to eject the coin at a predetermined period in the rotation of the said shaft to permit the said cylindrical member to be reversely rotated and restored to its normal position, and means for rotating it to restore it to this position, substantially as set forth.

10 In witness whereof, I have hereunto set my hand at Lagrange, Georgia, this 30th day of July, A. D. nineteen hundred and twenty-seven.

WALTER WILLIAM CADWELL.
